UNDERFEED STOKER FOR HOT AIR FURNACES

Leif Lee, Youngstown, Ohio; Halfdan Lee, execu-
tor of the Estate of said Leif Lee, deceased

Application July 30, 1936, Serial No. 93,513

3 Claims. (Cl. 126—110)

The present invention relates to an air heating furnace and more particularly to a furnace utilizing automatic stoker means for burning coke or other solid fuel.

The primary object of the invention is to provide an efficient air heating furnace which is inexpensive to construct, economical in operation, and which may be operated with a minimum of attention.

More specifically an object of this invention is to provide an air heating furnace which relies principally on radiation for its heating effect and in which the counterflow principle is used and applied between the incoming cold air and the outgoing heated air and between the flow of flue gases and the flow of the air being heated.

Another object of the invention is to provide a novel stoker mechanism which is simple in design and which is operative to under feed coke or other solid fuel to a bed of live coals, to agitate the bed and to dispose of the ashes.

Another object of the invention is to provide a novel combination of a furnace, air ducts associated therewith and automatic stoker means to form a highly efficient self-contained heating unit operable with a minimum of attention.

A further object of this invention is to provide novel means to regulate the flow of secondary air above the grates automatically in response to the pressure of the primary air below the grates or manually in such a manner that the primary air supply must be at its maximum before any secondary air is allowed to enter the combustion chamber.

These and other objects and advantages of the invention will become apparent from a consideration of the drawings and the following specification.

In the drawings:

Figure 1 is a side elevation of the assembled furnace with parts broken away and other parts in section.

Figure 2 is a part cross-sectional view taken along the line A—A of Figure 1, looking in the direction of the arrows.

Figure 3 is a cross-sectional view taken along the line B—B of Figure 1, looking in the direction of the arrows.

Figure 4 is a cross-sectional view taken along the line C—C of Figure 1, looking in the direction of the arrows.

Figure 5 is a cross-sectional view taken along the line D—D of Figure 1, looking in the direction of the arrows.

Figure 6 is a cross-sectional view similar to

Figure 3 but showing a modified means for supplying air for combustion.

Figure 7 is a top view of the air controlling means of Figure 6.

The heater and stoker assembly is supported on a floor plate 10 which in the illustrated embodiment of the invention is generally rectangular in form. An arch-shaped corrugated metal sheet 11 having front and rear end walls 12 and 13 is positioned on the plate 10 at one end thereof to form a combustion chamber. Resting on the plate 10 and parallel with but spaced from the side walls of the combustion chamber are two rectangular shaped ducts 14 having openings 15 extending along the lower portion of their outside walls for communication with the space within the combustion chamber. A wall 16 of refractory material is supported by and extends along the top of each duct 14. The refractory material is preferably light in weight so that it will not store a large amount of heat.

Extending transversely of the ducts at the ends thereof are the two supporting plates 17 and 18 which constitute spaced supporting means for the grate bars 19. The grate bars are preferably four in number, although any number may be used, and as shown they are provided with a plurality of perforations for supplying air to the fuel placed on the grates. The grate bars 19 are longitudinally oscillatable and are placed adjacent each other for a purpose to be later described.

An outer casing 20 supported on floor plate 10 encloses the entire assembly including the furnace, stoker and hopper. An intermediate casing 21 is housed within but spaced from the outer casing 20 and is spaced from but follows the general contour of the arch-shaped casing 11 of the combustion chamber. At its lower end the intermediate casing 21 is flanged outwardly at 22 to engage against the inner surface of the side wall of the outer casing 20. The spaces between the outer casing and the intermediate casing constitute ducts for the passage of cold incoming air while the spaces between the arch-shaped casing 11 and the intermediate casing 21 constitute ducts for the passage of air being heated by the combustion of fuel within the casing 11.

Positioned forwardly of the combustion chamber and on either side thereof is a circulating fan housed in the fan casing 25 having its inlet faced toward the center of the assembly. A fuel hopper having slanting side walls 21 is positioned above and between the two fan casings and a portion of the lower surface of the walls 21 constitutes a portion of the side walls of the ducts connecting the

cold air inlet duct above mentioned with the inlet of the fan casings 25. Vertical plates 30 form one wall of the connecting ducts to prevent air circulating through the heater from coming in contact with coal or coke dust emitted by the operation of the stoker mechanism.

A cross duct 31 utilizing a portion of the lower surface of the slanting wall 21 of the hopper as a wall and a portion of the outer casing 20 as another wall interconnects the inlet ducts of the two fans. The purpose of this duct is to equalize the pressure existing in the inlet ducts of the fans. This results in an equal volume of air passing through each fan and over each side of the heating surface 11 and consequently uniform and more efficient heating of the air.

The fans 25 discharge into the space between the casing 11 and the outer casing 20 at the bottom of the furnace below the flange 28. The air passes upwardly in intimate contact with the corrugated surface of casing 11 within the intermediate casing 27 and out through the outlet at the top of the furnace. The path of travel of the incoming and outgoing air is indicated throughout the drawings by arrows which show the application of the counterflow principle.

The products of combustion pass upwardly from the space between the refractory walls 16 and into the dome of the arch-shaped casing 11 from where they are drawn downwardly in contact with the inner surface of corrugated sheet 11 between the sheet and the outer surface of wall 16. Since the inlet openings 15 of conduits 14 are near the bottom of the furnace, the flue gases are required to travel substantially to the bottom of casing 11 before they escape from adjacent the surface of the casing 11. It can thus be seen that the flue gases are directed downwardly along the inner surface of casing 11 whereas the fan discharged air is caused to flow upwardly along the outer surface of casing 11.

Conduits 14 are connected at one end with a header 23, a box-like duct one wall of which is the lower portion of end wall 12. The duct 23 discharges into the longitudinally extending duct 24 which in turn discharges into the cross duct 26 which may be connected with a stack at either end thereof.

As shown in Figures 1, 3 and 4, a small transversely extending duct 32 is positioned along the top of header 23 and under the grate bars 19. The duct is open at its ends and is in communication with the discharge of the fans. The center portion of the rear wall of the duct is cut away at 33 to allow air coming into the ends of the duct to flow beneath the grate bars 19 to supply primary air for combustion.

Longitudinally spaced from the end wall 12 of the combustion chamber is the parallel plate 22 which forms the rear wall of the hopper and the front end of the space between the inner casing 11 and the intermediate casing 27. Plates 12 and 22 are provided with aligned openings to accommodate the grate bars 19 and passage of fuel from the hopper into the combustion chamber. Plates 34 connect the side edges of the openings for a portion of their length, a small opening 36 being left at the top on either side thereof. A bent strip 35 is positioned between the plates 12 and 22 and seals the space between the plates 12 and 22 from communication with the combustion chamber. The plates 12, 22 and 34 and the strip 35 form conduits for the entry of secondary air for combustion. The inlets of these conduits are in communication with the dis-

charge of the fans 25 and are controlled by pressure responsive valves 37 which are normally held closed by springs 38 but which are adapted to open and admit air above the grate bars 19 when the fan has attained a predetermined discharge pressure, the extent of opening being governed by the pressure attained.

A gate 39 having a rearwardly bent lower end 40 extending into the aligned opening in plates 12 and 22 is slidably supported on the front surface of plate 22 by straps 41 which may be adjustably anchored in lugs 42 by pins 43 passing through an eye in the upper end of straps 41. The bent end 40 of gate 39 supports an L-shaped block 44 of refractory material which extends the width of the aligned openings in plates 12 and 22. As shown, one side of the block 44 engages the inner surface of plate 12 and the block 44 is provided with an enlarged lower portion 45 to engage and be supported by the portion 40 of gate 39. The inclined surface of portion 45 of the refractory block 44 is provided with a plurality of spaced parallel grooves 46 therein which in conjunction with the plate 40 form a plurality of secondary air conducting orifices directed towards the grate bars 19 and into the furnace. As shown, the orifices are in communication with the secondary air conduit formed by the strip 35.

The grate bars 19 are arranged to oscillate longitudinally out of phase with each other and they may either be moved manually or be power driven. I have shown a preferred arrangement whereby the grate bars are power driven and in which the connecting rods 48 are utilized to connect the ends of the bars with the cranks of the crankshaft 50. The connecting rods 48 are pivotally connected with the grate bars by the pins 49. Crankshaft 50 is slowly driven by a pawl and ratchet mechanism 52-53 operated by an arm 54 oscillated by the crank 56 through an arm 55. A variable speed electric motor 58 is adapted to drive crank 56 through suitable reduction gearing 57. As shown, the cranks of the crankshaft 50 are angularly spaced 90° from each other. The purpose of this arrangement is to insure relative movement between adjacent bars and movement in opposite directions of adjacent bars at least during part of one revolution of the crankshaft and this results in agitating the bed of live coals on the grate bars and causes coals or lumps of solid fuel lying on the grate bars to be angularly oscillated.

The ends of the grate bars 19 extend beneath the outlet of the hopper and are each provided with a transverse shoulder 60 which propel solid fuel from the hopper along the path of travel of the grate bars. The fuel is prevented from returning in the direction of the hopper by pressure exerted by fuel sliding down the inclined wall 21 of the hopper. If desired, the inner surface of wall 21 may be lined with glazed tile or other smooth surfaced material to lessen friction between the fuel and the plate 21 and to prevent abrasion of the metal plate 21.

Extending across the rear end of the furnace 65 above and to the rear of the grate bars is the member 61 which has a depending lip 65 the rounded lower surface of which is positioned slightly above the upper surface of the grate bars and slightly to the rear of the end of the bars when the bars are in retracted position. This allows a small space between the edge of the grate bar and the lip when the grate bar is in retracted position to provide a passage for ashes but which prevents the falling of un- 75

burnt pieces of coal or coke by arresting their further movement. The ashes are shovelled off the plate 17 by the ends of the grate bars and fall into the pan 63 which pan may be removed through door 62.

It can thus be seen that the grate bars perform a plurality of functions, i. e., support the fire bed, admit air thereto, agitate the bed, feed fuel thereto and dispose of the ashes. The operation is such that the fuel is caused to be moved along the surface of the bars and thus under feed the fire. The lumps of fuel move into the fire zone with an erratic motion due to the relative movement of adjacent grate bars. The motion may be described as composed of linear, rotation and angular oscillation movements. An important result achieved by this feature is that the fire bed is agitated and a normally adequate supply of primary air for combustion is insured. Another result is that clinkers do not form as the relative erratic movement of the pieces of fuel effectively prevent amalgamation or fusion of the pieces which is the chief cause of clinker formation.

The operation of the device is obvious. A door 64 is provided whereby access may be had to the combustion chamber for the purpose of starting the fire. Fuel is fed from the hopper in the manner heretofore described. The quantity of fuel consumed and consequently the rate of heat delivery is determined by the vertical position of gate 39 and the speed of motor 58 which drives the grate bars 19 and the fans, the fans being mounted on shaft 65 driven by motor 58 through pulleys 66 and 67 and belt 68. Within certain limits of operation the automatic dampers 37 controlling the supply of secondary air for combustion remain closed but for higher rates of operation when the permeability of the grate bars and bed of live coals is such that an insufficient supply of primary air can reach the points of combustion the dampers 37 open in response to an increase of pressure from the fans and allow secondary air to flow to the bed of coals along the path previously described. The result is an intensification of the combustion with a consequent increase in the heat output.

Figures 6 and 7 illustrate a modification of the invention wherein primary and secondary air for combustion is taken directly from the atmosphere and natural draft is relied on to supply such air. The conduit 32 instead of being in communication with the discharge of the fans is connected with the atmosphere by means of a conduit 74 communicating with an opening 11 in the side wall of the outer casing 20. Another opening 72 in the outer casing is provided directly above the opening 11 and allows secondary air to pass from the atmosphere to the conduit formed by strip 35 through a duct 73. The openings 11 and 72 are controlled by a valve 75 which is cylindrically shaped to rotatably fit within the curved indentation of the side wall at the openings 11 and 72.

The cylindrically shaped valve is rotatably sup-

ported on the hinge pin 76 and is provided with a weighted operating arm 78 to which is attached an operating chain 77. The bracket 70 limits counter-clockwise rotational movement of valve 75 so that the upper opening 72 cannot be opened 5 when the lower opening 11 is closed. The arrangement is such that the lower opening must be completely open before any portion of the upper opening may be uncovered. This means that the maximum supply of primary air must 10 be furnished before any secondary air can be admitted.

If desired, the chain 77 may be coupled with means controlling the speed of operation of the motor 58 whereby when the motor is controlled 15 to run at a predetermined speed, either the opening 11 or both openings 11 and 72 may be uncovered.

While I have shown but one valve 75 it is obvious that another may also be employed—positioned on the opposite side of the furnace.

Having thus described my invention what I claim is:

1. An air heating furnace comprising a casing constituting a fuel supporting and combustion 25 chamber, a pair of spaced ducts arranged longitudinally in the lower portion of said casing and spaced from the side walls of said casing, a refractory wall supported on each of said ducts, a grate structure between said walls, each of said 30 ducts having openings in its outer side wall opposite the adjacent side wall of the casing, means connecting said ducts with a flue, and means to supply air to the space beneath the grate structure. 35

2. An air heating furnace comprising a casing, a plurality of longitudinally movable grate bars extending longitudinally into said casing, a hopper positioned at one end of said casing, the outer ends of said bars positioned below the outlet of 40 said hopper and provided with means to propel fuel from said hopper into said casing, a pair of ducts arranged longitudinally within the lower portion of said casing on either side of said bars, a refractory wall supported on each of said ducts 45 and spaced from the adjacent side wall of the casing, means positioned beneath said hopper to connect said ducts with a flue and means to supply air to the space beneath said bars.

3. An air heating furnace comprising a casing 50 forming a combustion chamber, fuel supporting means in said casing, a fuel hopper adjacent one end of said casing, said fuel supporting means being movable and operative to move fuel from the hopper into the casing, a flue duct in the lower portion of said casing and extending outwardly beneath said hopper, an air circulating device on either side of said duct arranged to circulate air in heat exchanging relation with the outer surfaces of said casing, and means positioned beneath said hopper and between said air circulating devices to operate the fuel supporting and moving means. 55
